UNITED STATES PATENT OFFICE.

PHILIP COOMBE, OF ISHPEMING, MICHIGAN.

FIRE-ESCAPE.

SPECIFICATION forming part of Letters Patent No. 625,147, dated May 16, 1899.

Application filed January 12, 1899. Serial No. 701,971. (No model.)

To all whom it may concern:

Be it known that I, PHILIP COOMBE, a citizen of the United States, residing at Ishpeming, in the county of Marquette and State of Michigan, have invented certain new and useful Improvements in Fire-Escapes; and I do hereby declare the following to be a full, clear, and exact description of the invention, such as will enable others skilled in the art to which it appertains to make and use the same.

This invention relates to trolley-hoist-support fire-escapes.

The object of the invention is to provide a hoisting basket or car adapted to be raised and lowered from the ground which may be adjusted at any point along the front or side of a building, so that passengers may be lowered or workmen or firemen may be raised opposite any part of the side of the building.

The invention consists in certain constructions and combinations hereinafter described, and specified in the claim.

In the drawings, Figure 1 is an elevation of a building, showing my invention applied thereto. Fig. 2 is a view at right angles to that of Fig. 1, showing a corner of the building at the roof, the supporting-brackets and the rails in elevation and the traversing car or trolley in section. Fig. 3 is a top or plan view of the car or trolley and the way or track.

1 is a building, as a hotel, boarding-house, factory, or business building, as the case may be, upon the top of which, at the edge of the roof, are secured brackets 2 2, to which are securely attached rails 3 3. These brackets are preferably arranged to extend upward and outward somewhat from the roof, so as to leave a space of fifteen inches, more or less, between the middle of the trolley and the wall 40 of the building.

Mounted on or in the rails or track is a trolley 4, consisting of a car having four trucks and having suspended from a central point between the trucks a guide-pulley or sheave 5.

The sheave is attached to the car by a swiveled connection 6, as clearly shown in Fig. 2 of the drawings. The rails are conveniently formed of sheet metal, each of the rails having its edges bent over to form a dove-tail channel for the trucks. By reason of this

construction there is no possibility of the trucks jumping or being detached from the track. Passing over the sheave 5 is a hoisting-rope 7, having attached to one extremity a car or basket 8, the other end passing around a sheave or guide-pulley 9 at or near the base of the building, the hoisting-rope being of sufficient length to permit the car to be raised from the ground to the roof of the building and lowered to the ground. A line 10 is attached to the car or basket in a suitable way and of sufficient length to reach the ground when the basket is at its highest position for hauling or swinging the car or basket outside of any projection on the building, such as a veranda or other obstruction. Obviously the main hoisting-rope 7 may be operated without passing around the guide-pulley or sheave 9, although such arrangement will ordinarily be one of convenience.

Connected with the car and leading over guide-pulleys or sheaves 11 11, at either end of the building, are shifting-cords or lanyards 12 12, extending to the ground for shifting the trolley along its track to any point along the side of the building. These lanyards or shifting-cords may also be led around sheaves or guide-pulleys 13 13 or not, as may be preferred. The shifting-cords or lanyards at the ends of the building may, if desired, be brought down through pipes, which would serve to protect them from fire and other injury, and in such case the guide-pulley or sheave will be arranged at or near the bottom of the pipes.

Obviously the track-rails may be formed in any suitable manner, provided they are given a dovetail channel; but the method of forming them from a single sheet or plate of metal bent into the form shown is preferred as being the most economical.

Having described my invention, what I claim as new, and desire to secure by Letters Patent, is—

The combination with a building, of brackets each consisting of two plates extending upward and outward from the roof of the building, one of the plates having a hanger-arm outside of the building and the other plate having a hanger-arm extended farther

from the building, a double track or way supported by and between said hangers, each rail of the track having a dovetail channel, a trolley having trucks adapted to fit and work in
5 said dovetail ways, a passenger car or basket suspended from the trolley, a hoisting rope or cable for raising and lowering the passenger-car, and means for traversing the trolley

backward and forward along the side of the building, substantially as described.

In testimony whereof I affix my signature in presence of two witnesses.

PHILIP COOMBE.
